UNITED STATES PATENT OFFICE.

RALPH S. PIPER, OF CHICAGO, ILLINOIS.

COUPLING TRANSFORMER FOR RADIO SYSTEMS.

Application filed June 15, 1922. Serial No. 588,546.

To all whom it may concern:

Be it known that I, RALPH S. PIPER, a citizen of the United States, residing at Chicago, in the county of Cook and State of Illinois, have invented certain new and useful Improvements in Coupling Transformers for Radio Systems, of which the following is a specification.

My invention relates to wireless input circuits and has as one primary object an improvement in the character of coupling between the antenna circuit and the oscillation circuit of the detector tube which is commonly used in such circuit. The amounts or quantities of energy concerned in the operation of such circuits is almost infinitesimal and one purpose of this invention is to conserve all of the energy possible and present it to the input circuit with the least possible loss.

It is well known that the best possible conditions for energy transference from one circuit to another through a magnetic coupling of the same, requires the use of a tight or close coupling. All low frequency commercial power circuits are coupled in consonance with this principle; but in the case of wireless reception circuits, which of course, are of very high frequencies, the input circuit is concerned not alone with energy transference but must discharge other functions, such as detection and amplification, and accordingly a compromise must be made between a close coupling which would give the maximum power transference and a more or less loose coupling which has sufficient elasticity and flexibility to permit of attainment of resonance between the several circuits involved.

As far as I am aware, it has been the practice heretofore, to extend this loose coupling characteristic throughout the range of the coupling. Usually the coupling circuits are made movable with respect to each other, and hence no part of the circuits can be said to have a strictly close coupling.

I have discovered, that it is possible to divide the coupling into sections, or portions, some of which may be as closely coupled as in ordinary power transformer circuits and that the functions of a loose coupling may be relegated to certain other portions of the

winding which present a decided loose coupling characteristic. The result of this arrangement is, that the tight coupling portions will give exceptionally good energy transference and there will yet be sufficient flexibility in the coupling as a whole, to permit of the establishment of resonance relation upon which the efficient operation of a reception set is conditioned as regards detection and amplification.

As is well understood, when the antenna circuit is tuned to the passing radio waves, oscillations are set up in the antenna circuit and these oscillations induce oscillations which cause alternating currents to flow in the secondary circuit. If the secondary circuit is put in resonance with the primary antenna circuit, these secondary oscillations will be of maximum strength.

The inductive coupling between the antenna circuit and the secondary circuit may be varied without very greatly changing the wave length or oscillation frequency of either. This inductive coupling may be either close or tight or else it may be loose or open. Close or tight coupling is secured by bringing the primary and secondary coils into close relation, as by winding the layers of the two coils together side by side or by winding one over the other, or by the auto-transformer arrangement; while loose or open coupling is obtained by separating the coils some distance from each other.

When tight coupling is employed the mutual induction effect is strong, producing currents of greatly increased strength in the secondary circuit, but rendering the latter exceedingly sensitive and difficult to maintain in proper adjustment of resonance under varying conditions. Loose coupling, on the other hand, greatly improves the tuning qualities or selectivity. Less energy is collected from the antenna circuit and the effective resistances of both circuits are reduced but, necessarily, the signal strength is considerably decreased.

The purpose of my invention is accordingly to provide an inductive coupling between the antenna circuit and the secondary circuit which secures the increased signal strength afforded by a tight or close coupling and at the same time gives the increased

selectivity and improved tuning qualities of the loose coupling.

In the following description I shall refer to the accompanying drawings, in which 5 Figure 1 is a perspective view, partly broken away, of a coupling transformer embodying my invention; Fig. 2 is a side elevation, partly broken away of a similar transformer showing a sliding contact for varying the 10 primary turns in circuit and taps connected to a plurality of points in the secondary; Figs. 3 and 4 are vertical sectional views taken on the lines 3—3 and 4—4, respectively of Fig. 2; and Figs. 5, 6 and 7 are 15 diagrammatic views illustrating the manner of connecting the coupling transformer to different radio receiving circuits.

In Fig. 1, I have shown one manner of constructing my coupling transformer by 20 winding the coils upon a cylinder 10 of bakelite or other suitable insulating material. The secondary coil 12 is first wound over opposite peripheral sections 10^a separated from the body of the cylinder 10 by 25 longitudinal slots 11 through which the turns of the wire are threaded. The primary coil 14 is then wound upon the tube, lying in close contact with the exposed peripheral portions of the secondary coil 30 wound on sections 10^a. This construction brings the primary and a portion of the secondary into close inductive relation forming a tight coupling throughout those portions which overlie the sections 10^a of the cylinder, while the intermediate portions 12^a of 35 the secondary which extend across the interior from one side of the cylinder to the other are in open inductive relation or loosely coupled with the primary. It will 40 be seen that the loose coupled portions of the secondary, extending between the slots 11, constitute in effect a chord of a circle formed by a section of the cylinder. And it will be noted that as the secondary winding 45 progresses along the chord, the degree of coupling varies. In order to take advantage of this varying coupling factor, a series of taps are provided, the connections to which may be mechanically varied, as illustrated structurally in Figs. 2, 3 and 4, and 50 diagrammatically in Fig. 5, and the amount of mutual induction between the coils in the loosely coupled portions will vary, of course, according to the distance separating the 55 coil sections 12^a and the primary 14. The amount of tight coupling may be changed by making the cylinder sections 10^a, which support the secondary, wider or narrower, that is, by making the sections 12 extend over a 60 greater or lesser arc of the cylinder. Likewise the degree of loose coupling can be varied by changing the shape of the tubular support or by varying the relative position of the coils. I have shown a cylindrical 65 supporting tube but it is evident that I may

employ an ellipsoidal, polygonal or other suitable shape for the purpose of obtaining the desired ratio between the tight and loose coupled portions and to vary the degree of loose coupling and to produce the proper 70 gradation of mutual induction over the loosely coupled peripheral portions to suit different conditions. In assembling the windings it is obvious that the coils may be first wound over a properly shaped mandrel 75 or former and be maintained in shape by varnish or other coating after the withdrawal of the mandrel or form.

My transformer may be connected in any 80 wireless circuit to constitute the inductive coupling between the antenna and the secondary circuits. I have indicated in Fig. 7 one of the usual circuit diagrams, the several 85 elements being indicated by the well-known conventions and designated by the reference characters usually applied to them so that they will be recognized by engineers without further explanation. In this diagram I have endeavored to indicate close and loose coupling between the primary 14 and the secondary 90 12 by positioning the central part of the secondary close to the primary while the ends of the secondary taper outwardly therefrom.

In Fig. 7 the coils of the coupling transformer are not provided with any adjustable connections, the terminals of the primary being connected to the aerial and to ground, and the secondary terminals being connected to the grid and to the filament of the audion tube. In this case the tuning is effected by the adjustable condensers c_1 in the antenna and C in shunt to the terminals of the secondary. In order to increase the range of adjustment I provide means for 105 varying the effective lengths of both primary and secondary coils. One means of accomplishing this is shown in Fig. 2 and diagrammatically in Fig. 5. A sliding contact 15, which may be connected to ground, as indicated in Fig. 5, or to the aerial, may be moved along the primary, the insulation being removed from the wires along its path. The secondary is provided at intervals with 110 taps t which are connected to switch contacts 16, over which the switch arm 17 is moved as indicated in Fig. 5. In the diagram of Fig. 5 I have illustrated another known arrangement of circuits in which the head-phone HP is connected to the oscillation circuit of the secondary through a crystal detector d .

It is evident that the primary may be provided with a double slider, one connected to the aerial and the other to the ground 125 connection if desired, as indicated diagrammatically in Fig. 6. The sliding contacts 15 may be located over parts of the primary which are not adjacent to the secondary, as indicated in Fig. 4 so that there is no danger 130

that the slider will contact with the secondary.

As will be understood by those familiar with radio systems the antenna circuit is 5 tuned to the incoming waves by adjusting the effective length of the primary 14 and the adjustable condenser c_1 , and the secondary oscillation circuit is then placed in resonance with the primary circuit by adjusting the effective length of the secondary 10 and adjusting the variable condenser C.

It is evident that the antenna circuit is in the best receptive condition for the incoming waves when the primary is in resonance with the received oscillations. Owing 15 to the inductive relation described above of tight and loose coupled sections, it is believed a reaction is set up between the field of the primary and secondary respective close and loose coupled sections. These 20 sections of each winding are electrically connected in series, and it is believed that magnetically there occurs automatically a shift or adjustment in the coupling under different 25 conditions, such that the coupling improves the selectivity according to the requirements of resonance. This automatic change in coupling causes an inherent tendency 30 of my transformer to shift into resonance and to maintain this condition which greatly facilitates obtaining exact conditions of resonance. This is only my supposition based upon actual experience with this apparatus, but I do not wish to be bound by 35 this theory of operation.

While I have illustrated my invention in connection with the usual "indirect inductive coupling" it is obvious that many advantages thereof apply equally well to the "direct inductive coupling," both of which are 40 well known in the art, as explained on pages 267 and 268 of a book entitled "The principles underlying radio communication" (sec-

ond edition) published by the Signal Corps, U. S. Army.

I claim:—

1. In an inductive coupling, an outer winding of cylindrical contour and an approximately prism-shaped inner winding linked therewith.

2. A coupling transformer for radio systems, comprising a primary coil of tubular form and a secondary coil having opposed plane faces extending as chords to sectors of the tubular primary coil.

3. A coupling transformer for radio systems, comprising a primary coil and a secondary coil in fixed relation and of different cross-sectional configuration, the turns of said respective coils having a common area, and each coil having also a spaced area with respect to the other coil.

4. A coupling transformer for radio systems, comprising a primary coil and a secondary coil in fixed relation, certain peripheral sections of the turns of the respective coils being in contiguous superposed relation, and other peripheral sections of the turns of said coils being spaced apart.

5. A coupling transformer for radio systems, comprising a tubular insulating support, a secondary coil wound upon symmetrically disposed peripheral sections of said support, intermediate connecting sections of the secondary passing through slots in the support and across the interior thereof, and a primary coil wound upon the support and superposed upon the exposed peripheral sections of the secondary, whereby said secondary forms a tight magnetic coupling with the primary at said superposed portions and a loose coupling therewith at said intermediate portions.

In testimony whereof I affix my signature.

RALPH S. PIPER.
